TUBULAR KNITTED FABRIC AND ARTICLE

Bernard Thornton Reymes Reymes-Cole, Burbage, near Hinckley, John Maurice Reymes Reymes-Cole, Hinckley, and David Norman Reymes Reymes-Cole, Melton Mowbray, England, assignors to The Kendall Company, Boston, Mass., a corporation of Massachusetts

Original application May 25, 1949, Serial No. 95,336, now Patent No. 2,703,970, dated March 15, 1955. Divided and this application June 4, 1954, Serial No. 434,554

15 Claims. (Cl. 66—183)

This invention concerns improvements in tubular knitted fabric and articles made thereof and has particular reference to seamless hose capable of being produced by means of the circular knitting machine and method disclosed in copending U. S. application Serial No. 95,336, filed May 25, 1949, and issued as Patent No. 2,703,970, dated March 15, 1955, from which the present application is divided and to which reference is directed for details of the machine and method referred to.

An object of the invention is to provide a fashioned seamless fabric and more particularly a fashioned seamless hose having an appearance not hitherto obtainable in such articles. A further object is to produce a fashioned seamless stocking simulating in appearance conventionally fully fashioned stockings.

The conventional seamless stocking suffers from the disadvantage that since the leg is knitted throughout upon a uniform number of needles, it is produced as a tube having a substantially uniform girth. It is common practice to minimize this disadvantage by what is known as "stiffening," which consists in so adjusting the machine as knitting proceeds down the leg that the stitch length is progressively reduced with a resultant progressive diminution in the girth, and by subsequently accentuating the taper by drawing the stockings onto a board or form, having the shape of a leg and foot, and submitting it thereon to heat, moisture, and pressure with the result that the stocking is set to the shape of this board. Even so, the resultant stocking does not fit so well as does a fully fashioned stocking which article is the product of a Cotton's Patent or other straight bar knitting machine. Fully fashioned stockings are initially knitted as a flat selvedged blank and the selvedge edges of the blank are subsequently seamed together; their excellent fit is in the main due to the fact that the number of wales is decreased, as knitting proceeds down the leg, by a narrowing process which consists in the periodic inward transfer of a group of wales at each selvedge. The desirability has long been recognised, of fashioning the leg of a seamless stocking by varying the number of wales during its production by rotary knitting on a circular knitting machine but heretofore attempts to this end have not met with commercial success, and a specific object of the present invention is the production of a fashioned, seamless stocking free from the major defects of conventional seamless stockings and of a character adapted to meet public requirements.

The expression "stocking" is employed herein not only to include a conventional stocking but also analogous articles such for example as socks and three-quarter hose, and further to include a blank for a stocking or the like, a blank being a partially completed stocking or the like at a stage after it has been knitted on the machine but at which it still requires seaming operations to be effected on it.

The invention resides in the features set forth in the

2

appended claims. These features and the objects and advantages of the invention will appear more fully from the description of preferred embodiments of the invention shown by way of example in the accompanying drawings in which:

Figure 1 is a diagram showing the structure of a portion of fashioning fabric according to this invention;

Figure 2 is a similar view illustrating the manner in which the introduction of additional wales shapes or fashions the fabric, and illustrating the evening-out of the loops;

Figures 3, 4 and 5 show stockings produced by the exercise of this invention, while

Figure 6 illustrates a modified form of stocking.

15 In Figure 1 the needle wales are lettered *a* to *v* inclusive. In the group of wales *f* to *p* inclusive there are certain wales such as *g*, *i*, *k*, etc. (termed odd wales) which extend throughout the length of the fabric and other wales *f*, *h*, *j*, etc. (termed even wales or fashioning wales) which only commence at intermediate stages in the production of the fabric. The loops of these even wales are somewhat longer than the loops of the odd wales. Likewise beyond the said group of wales the loops of the even wales *b*—*d* etc. are longer than the loops of the odd wales *a*—*c* etc.

20 The difference in loop size is such that the fabric produced within the group of wales *f*—*p* before and after the introduction of the additional wales *g*, *i*, *k*, etc. is substantially visually undistinguishable from the fabric outside the group of wales.

25 As will readily be appreciated and is apparent from Fig. 2 the introduction of the additional wales causes the fabric to be shaped or fashioned, Figure 2 illustrating the fact that the loop size evens out. Moreover at the commencement of each introduced wale there is formed a small hole such holes being indicated at 100 in Figure 2, and in the application of the invention to a lady's stocking these holes simulate the fashioning marks of a fully fashioned stocking.

30 40 It is here to be pointed out that in each course of the fabric a maximum of two kinds of fabric is produced. That is to say, fabric knitted on consecutive odd and even needles and consisting of short and long loops in alternation, and fabric knitted on the odd needles and consisting of loops all of one size.

35 45 The knitted fabric in its preferred form before boarding thus consists of at least one pair of longitudinally abutting non-fashioned and fashioned areas produced on a portion of the needle series having fashioning needles. These longitudinally abutting areas comprise wales extending the length of said abutting areas having non-selected loops of a predetermined short length which in the non-fashioned area are connected by ties of relatively great length. In the adjacent fashioned area fashioning wales are introduced alternating with or closely spaced between said non-selected loop wales in the stead of said long ties and having selected loops of greater length. The selected and non-selected loops are chosen of such relative length to cause all of said loops to be reformed to substantially the same average length as they are withdrawn from the machine, and more particularly when the completed fabric is boarded. In each of the laterally adjacent non-fashioned areas at each side of

50 55 60 65 70 the longitudinally adjacent areas above referred to, the fabric may be composed of wales all having loops of average length but preferably is composed of wales having non-selected loops of short length extending through said non-fashioned area and other wales extending through said non-fashioned areas having selected loops of greater length. All of said selected and non-selected loops are chosen of such relative lengths to cause all

of said loops to be reformed to substantially even lengths when boarded, so that the fabric in each of said fashioned and non-fashioned areas is completely indistinguishable from the fabric of every other said area.

As hereinafter mentioned the fashioning is effected by introducing fashioning needles and their sinkers into knitting activity, these fashioning needles being every second needle in a group of needles. In the production of a stocking such as that shown at 101 in Figure 3 with a conventional heel 58 and toe 59, because the fashioning needles are introduced progressively (working inwards from the outer ends of the group) the lines 100a produced by the fashioning marks 100 converge upwardly. On the other hand if the fashioning needles are introduced progressively, working outwards from the centre of the group, the fashioning marks 100a diverge upwardly as shown in the stocking 102, Figure 4.

In addition to the leg fashionings 100a thigh fashionings 100b may be produced in a similar manner.

Figure 5 shows at 103 a further stocking which in addition to the calf fashionings 100a has foot fashionings 100c. In order to produce these foot fashionings, fashioning needles are interspersed in a further group of needles substantially diametrically opposed to the previously mentioned group. Indeed the two groups may constitute all the needles of the machine. In manufacture, since the stocking is knitted toe upwards the fashioning needles for producing the foot fashionings 100c are introduced at a time when the foot bottom is knitted on every second needle only, the intervening needles being fashioning needles which are held inactive and are only introduced when it is required to produce the leg fashionings 100a.

A further modified stocking is shown at 104 in Fig. 6. It will be seen that the two lines of leg fashionings 100a converge upwardly. Between them there is a gap 105 in the fabric, the edges of which gap are parallel to the two fashioning lines. Thus when the edges of the fabric at opposite sides of the gap are seamed together the two fashioning lines 100a are brought parallel as in a fully fashioned stocking. The gap is preferably produced by knitting the leg as a seamless tube and cutting the requisite fabric from it. Alternatively it may be produced while the leg is being knitted by initially withholding a block of needles from knitting activity, thereby forming a gap across which floating threads are laid, and introducing these needles progressively as knitting proceeds thereby to narrow the gap in known manner. The gap may extend through the heel and along the foot bottom.

The fabric and the stocking as described herein may be made on a circular knitting machine conveniently of a form as disclosed in the specification of co-pending U. S. patent application No. 95,336 and by the use of the method described in said specification. Briefly this machine is of the type organized to knit tubular fabric by rotation and may also knit a pouch by oscillation and comprises a tricked cylinder equipped with latch needles and needle controlling instruments operated by appropriate cam means, and also provided with cam controlled loop forming sinkers. Closely spaced among a group of needles which may be termed non-fashioning needles there are interposed fashioning needles which are initially maintained inactive and are brought sequentially into knitting activity to commence fresh wales for fashioning purposes. As during the knitting of a non-fashioned area of fabric before the fashioning needles are brought into knitting activity the non-fashioning needles in the said group are more widely spaced than active needles outside that group, arrangements are incorporated in the machine whereby relative loop drawing movements are imparted to spaced active needles and associated sinkers outside the group which differ from those imparted to all other non-fashioning needles and their sinkers in such a way that discrepancies in loop size become evened out

in the finished fabric, so that the fabric produced within the group of needles is substantially visually indistinguishable from that produced by needles outside the group. Similarly the fashioning needles, when active, and their sinkers have imparted to them relative loop drawing movements which differ from those imparted to the non-fashioning needles in the group for a like purpose.

As a result of the manner of knitting carried out by said machine as more fully described in co-pending application No. 95,336 the fabric produced in fashioned areas is caused to have a loop structure substantially visually indistinguishable from that produced in adjacent non-fashioning areas and as a consequence a seamless hose is produced by rotary knitting having characteristics simulating those of a conventional fully fashioned hose produced by reciprocatory knitting on a flat bar machine.

The differences in loop sizes produced as before indicated during the knitting of the fabric are substantially imperceptible when the fabric comes from the machine as there is some tendency for the loops to even out after leaving the needles. Subsequently the fabric is subjected to boarding and thereafter any differences in the fabric structure are entirely imperceptible.

We claim:

1. Plain knitted tubular fabric having a fashioned area comprising wales having non-selected loops of one length extending through the length of said area, and other fashioning walls of lesser length closely spaced among said first mentioned wales having selected loops of greater length, said selected and non-selected loops being chosen of such relative lengths to render the fabric of the fashioned area in portions including said fashioning wales substantially indistinguishable from portions not including said fashioning wales.

2. An article of manufacture comprising a boarded tubular knitted fabric having a fashioned area comprising wales extending through the length of said area having non-selected loops of one length and other fashioning wales of lesser length closely spaced among said first mentioned wales and having selected loops of greater length, said selected and non-selected loops being chosen of such relative lengths whereby the fabric loops when boarded are substantially evened out and portions of the fabric area including said fashioning wales are rendered substantially indistinguishable from portions of said area not including said fashioning wales.

3. A circularly knitted stocking having its leg portion fashioned by incorporation at closely spaced intervals within a selected group of non-fashioning wales formed of loops of one length of fashioning wales formed of loops of a different length extending only from fashioning locations, the relative lengths of loops in the fashioning and adjacent non-fashioning wales being such that the fabric throughout said group of wales is substantially visually indistinguishable from that outside said group.

4. A circularly knitted stocking having at least its leg portion fashioned within a rearward group of wales consisting of non-selected loops of one length by incorporation of fashioning wales consisting of selected loops of a greater length at closely spaced intervals laterally of said group and extending only from fashioning marks spaced longitudinally of said group, the relative lengths of the selected and non-selected loops in said group of wales being such that the fabric structure throughout the whole length of said group of wales is substantially visually indistinguishable from the fabric structure outside said group of wales.

5. An intermediate product which comprises an unboarded tubular knitted fabric having fashioned areas and laterally adjacent non-fashioned areas comprising wales in each of said areas having selected loops of one length including fashioning wales in the fashioned areas

closely spaced among wales having non-selected loops of a different length from the selected loops, said loops being chosen of such relative lengths to render the fabric of the fashioned areas substantially indistinguishable from the fabric of the non-fashioned areas.

6. An intermediate product which comprises an unboarded tubular knitted fabric having fashioned areas and laterally adjacent non-fashioned areas composed of wales having non-selected loops of one length extending through each of said areas, and other wales having selected loops of greater length closely spaced among said non-selected loop wales in each of said areas including fashioning wales of lesser length in said fashioned areas, said selected and non-selected loops being chosen of such relative lengths to render the fabric of the fashioned areas substantially indistinguishable from the fabric of the non-fashioned areas.

7. An article of manufacture comprising a boarded tubular knitted fabric having fashioned areas and laterally adjacent non-fashioned areas, each of said areas comprising wales extending the length of said areas having non-selected loops of one length, and in said non-fashioned areas other wales closely spaced therebetween having selected loops of a different length, and in said fashioned areas fashioning wales of shorter length having loops of said different length, the selected and non-selected loops being chosen of such relative lengths to cause all of said loops to be reformed to substantially even length when boarded and thereby to render the fabric of the fashioned areas substantially indistinguishable from the fabric of the non-fashioned areas.

8. An article of manufacture comprising a boarded tubular knitted fabric having fashioned areas and adjacent non-fashioned areas composed of wales having non-selected loops of one length extending through each of said areas and other less extensive wales having selected loops of greater length provided for fashioning purposes and closely spaced among a group of the first said non-selected loop wales, the selected and non-selected loops being chosen of such relative lengths to cause all of said loops to be reformed to substantially even lengths when boarded and thereby to render the fabric of the fashioned areas substantially indistinguishable from the fabric of the non-fashioned areas.

9. A fashioned hose formed from boarded tubular knitted fabric having rearwardly disposed in the leg portion fashioned areas and adjacent non-fashioned areas including wales having non-selected loops of one length extending through each of said areas and in said fashioned areas other less extensive wales of different lengths provided for fashioning purposes having selected loops of a greater length and closely spaced among a group of the first said wales, the selected and non-selected loops in said fashioned area being chosen of such relative lengths to cause all of said loops to be reformed to substantially even lengths when boarded and thereby to render the fabric of the fashioned areas substantially indistinguishable from the fabric of the non-fashioned areas.

10. An article of manufacture comprising a boarded tubular fabric having fashioning areas and laterally adjacent non-fashioning areas composed of non-selected loops of one length extending through each of said areas, and alternating therewith other wales having loops of greater length including fashioning wales of less extent in said fashioning areas, the selected and non-selected loops in the respective wales being chosen of such relative lengths to cause all of said loops to be reformed to substantially even lengths when boarded and thereby to render the fabric of the fashioned areas substantially indistinguishable from the fabric of the non-fashioned areas.

11. An intermediate product which comprises an unboarded knitted fabric having longitudinally abutting non-fashioned and fashioned areas disposed laterally be-

tween non-fashioned areas, said longitudinally abutting areas comprising wales extending the length of said abutting areas having non-selected loops of short length and connecting ties of relatively great length, and fashioning wales having selected loops of greater length commencing within said fashioned area and spaced between said non-selected loop wales in the stead of said long ties, said selected and non-selected loops being chosen of such relative lengths to render the fabric of the fashioned areas substantially indistinguishable from the fabric of the non-fashioned areas.

12. An intermediate product which comprises an unboarded knitted fabric having longitudinally abutting non-fashioned and fashioned areas disposed laterally between non-fashioned areas, said longitudinally abutting areas comprising wales extending the length of said abutting areas having non-selected loops of short length and connecting ties of relatively great length, and fashioning wales having selected loops of greater length commencing within said fashioned areas and closely spaced between said non-selected loop wales in the stead of said long ties, the selected and non-selected loops being chosen of such relative length to cause all of said loops to be reformed to substantially even lengths when boarded and thereby to render the fabric in each of said areas indistinguishable from the fabric of every other area.

13. An intermediate fabric in accordance with claim 12 in which the longitudinally abutting non-fashioned and fashioned areas have adjacent thereto at least one laterally adjacent non-fashioned area composed of wales having non-selected loops of short length extending through said non-fashioned area, and other wales closely spaced therebetween having selected loops of greater length, all of said selected and non-selected loops being chosen of such relative lengths to cause all of said loops to be reformed to substantially even lengths when boarded, and thereby to render the fabric in each of said fashioned and non-fashioned areas substantially indistinguishable.

14. A fashioned hose formed from boarded tubular knitted fabric having longitudinally abutting non-fashioned and fashioned areas disposed laterally between non-fashioned areas, said areas forming the entire girth of the fabric, said longitudinally abutting areas comprising wales extending the length of said abutting areas having non-selected loops of short length and connecting ties of relatively greater length, and fashioning wales having selected loops of greater length commencing within said fashioned areas and closely spaced between said non-selected loop wales in the stead of said long ties, and each laterally adjacent non-fashioned area consisting of wales extending through said laterally adjacent non-fashioned area having non-selected loops of said short length, and other wales alternating therewith extending through said laterally adjacent non-fashioned area having selected loops of said greater length, all of said selected and non-selected loops being chosen of such relative lengths to cause all of said loops to be reformed to substantially even lengths when boarded and thereby to render the fabric in each of said fashioned and non-fashioned areas completely indistinguishable.

15. An intermediate product which comprises an unboarded knitted fabric having longitudinally abutting non-fashioned and fashioned areas disposed laterally between non-fashioned areas, said laterally disposed non-fashioned areas comprising wales extending the length thereof having loops of average even length, said longitudinally abutting areas comprising wales extending the length of said abutting areas having non-selected loops of short length and connecting ties of relatively great length, and fashioning wales having selected loops of greater length commencing within said fashioned areas

and closely spaced between said non-selected loop wales in the stead of said long ties, the selected and non-selected loops being chosen of such relative length to cause all of said loops to be reformed to substantially even lengths when boarded.
